CONTAINER CAPPING MACHINE

Manuel S. Resina, Brooklyn, N. Y.; Rosa Resina, executrix of said Manuel S. Resina, deceased, assignor to Resina Automatic Machinery Co. Inc., Brooklyn, N. Y., a corporation of New York

Application August 3, 1948, Serial No. 42,305

2 Claims. (Cl. 226—81)

1

This invention relates generally to container capping machines and more particularly to those of the automatic type.

It is among the principal objects of the present invention to provide a machine of the class described which is capable, with suitable adaptation, of handling a range of container and/or cap sizes.

Another object herein lies in the provision of container capping machines in which the caps may be spun over the edge of the container opening to produce an efficient seal.

Another object herein lies in the provision of a machine of the class described which acts upon the containers and caps at a rapid rate.

A still further object herein lies in the provision of hopper and hopper feed structure which consecutively feeds properly positioned caps in correlation to the positioning of the containers being capped.

Another object herein lies in the provision of mechanism which stops the capping operations when the containers are improperly positioned, so as to prevent damage to the machine and the containers and caps.

The present constructions include safety features which act to prevent certain types of accidental injury to the operator.

These objects and other incidental ends and advantages will more fully appear in the progress of this disclosure and be pointed out in the appended claims.

In the drawings, similar reference characters designate corresponding parts throughout the several views:

Figure 1 is a fragmentary front elevational view of an embodiment of the invention.

Figure 2 is an enlarged fragmentary elevational view showing in detail the upper right hand portion of Figure 1.

Figure 2A is an enlarged fragmentary vertical section on plane 2a—2a of Figure 2 with cap pushed in place.

Figure 3 is an enlarged fragmentary horizontal sectional view as seen from the plane 3—3 on Figure 9.

Figure 4 is an enlarged fragmentary elevational view partly in section as seen from the plane 4—4 on Figure 2.

Figure 5 is a fragmentary elevational view partly in section of the upper right hand portion of Figure 4 showing the parts in an altered position thereof.

Figure 6 is an enlarged fragmentary sectional view as seen from the plane 6—6 on Figure 4.

2

Figure 7 is a fragmentary vertical sectional view as seen from the plane 7—7 on Figure 9.

Figure 8 is an enlarged fragmentary vertical sectional view as seen from the plane 8—8 on Figure 4.

Figure 9 is an enlarged fragmentary vertical sectional view as seen from the plane 9—9 on Figure 13.

Figure 10 is a fragmentary vertical sectional view as seen from the plane 10—10 on Figure 9.

Figure 11 is a fragmentary plan view partly in section as seen from the plane 11—11 on Figure 1.

Figure 12 is a fragmentary plan view partly in section as seen from the plane 12—12 on Figure 1.

Figure 13 is an enlarged fragmentary plan view as seen from plane 13—13 on Figure 1.

Figure 14 is an enlarged fragmentary vertical sectional view as seen from the plane 14—14 on Figure 13 when a container is in a cap receiving position.

Figure 15 is an enlarged fragmentary vertical sectional view corresponding to Figure 14, but showing the altered position of the parts when there is no container in the cap receiving position.

Figure 16 is a fragmentary vertical sectional view as seen from the plane 16—16 on Figure 13.

Figure 17 is an approximate cam displacement schematic diagram, showing linear displacement of cams with respect to degree phase rotation.

Figure 18 is an enlarged fragmentary vertical elevational view as seen in the upper central portion of Figure 1.

Figure 19 is an enlarged fragmentary vertical sectional view as seen from the plane 19—19 on Figure 18.

Figure 20 is an enlarged fragmentary plan view as seen from above Fig. 18.

Figure 21 is an enlarged sectional view as seen from the plane 21—21 on Figure 19.

Figure 22 is a view somewhat similar to Figure 3, but showing a modified construction.

Figure 23 is an enlarged fragmentary horizontal sectional view as seen from the plane 23—23 on Figure 24.

Figure 24 is an enlarged fragmentary sectional view as seen from the plane 24—24 on Figure 22.

Figure 25 is a fragmentary sectional view corresponding to the left portion of Figure 24, but showing the parts in a cap pick-up position.

Figure 26 is a fragmentary sectional view corresponding to Figure 25, but showing the parts in a cap depositing position.

Figure 27 is a fragmentary bottom perspective

view of the cam in the upper left portion of Figure 22.

In accordance with the invention, the machine 30 comprises broadly: container conveyor means 32; container movement guide means 34; hopper and cap supply means 36; container cap feeding means 38; container cap transfer means 40; cap placing means 42 and safety mechanism 43; container positioning means 44 and safety mechanism 45; container holding means 46 and safety mechanism 47 (Fig. 12); and cap closing means 48 and safety mechanism 49.

Turning to Fig. 1, the machine 30 includes a frame 58 upon which is mounted a motor 51, which through the belt 52 drives the speed reduction device 53. Device 53 drives the main drive shaft 54.

Located at the forward upper portion of the frame 58 is the container conveyor means 32 which includes a continuous conveyor link belt 56 carried by rotatable supports 58 and 60 therefor. The support 60 may be driven by the chain 62 and the sprocket 64, the latter being suitably supplied with power from the main drive shaft 54. The upper rim of the belt 56 is supported in a horizontal position by the platform 66, while the lower rim is supported by the shelf 68. During operation, the belt 56 moves in the direction of the arrows 70.

The container guide means 34 include the rails 72 and 74 along which the rear surfaces of the containers (generally indicated by reference character 100) slide, and the plates 76 and 78 supported by the uprights 80 and 82 against the rear portions of which the front surfaces of the containers slide.

Projecting perpendicularly up from the upper surface of the platform 66 are a pair of stationary posts 84 and 86 upon which is slideably supported a carriage 88. The carriage 88 includes a top plate 90 and a bottom plate 92 and is adjustable in height, as a unit, with respect to the platform 66 by means of a threaded post 94. The post 94 projects downward from the plate 92, extends through a hole in the platform 66 and carries a nut and handwheel 96. The bottom plate 92 is suspended from the top plate 90 by four tie-rods 98, 102, 104 and 106. The carriage 88 supports the hopper means 36 above it upon supports 108, 110, and 112. Also above the top plate 90 is the gear train 114 for power take-off for the cap closing means 48. Disposed between the top plate and extending below the bottom plate of the carriage 88 are the lower portion of the cap feeding means 38, the cap transfer means 40, cap placing means 42, mechanism 43, and cap closing means 48 and mechanism 49. This enables the operator to adjust the machine 30 to accommodate it to containers of different height.

In the operation of the machine 30, a series of containers 100 is placed upon the conveyor belt 56 at the area 116 (Fig. 1). As the first container is moved to the left as viewed in said figure, it strikes against the container positioning means 44. The means 44 includes a cam 163, which cam in turn causes continuous oscillation of the arm 160 having the upright projection 164 normally passing too far to the right (Fig. 12) of the catch member 154 to engage the same. The finger 150 member 154 is normally kept forward in the path of the containers 100 by the spring 165 which acts upon the slideable member 142 in the slide bearing 139. The lever 145 is pivotally mounted on the forward end of the slideable member 142. The pressure of the container against the finger 150 causes

the lever 145 to rotate clockwise against the action of spring 173, thus bringing the catch member 154 into the path of the oscillating projection 164 resulting in engagement, which will draw the finger 150 from the path of the containers allowing one to pass to the left. The speed of the conveyor and the arrangement of the cams 163 and 71 is such that the container holding element 55 is retracted until the container just released by the finger 150 reaches the cap closing position 116 (Fig. 12); whereupon the element 55 moves forward to clamp the container in a fixed position against the rails 72 and 74 (Fig. 1) where it can be acted upon by the means 48. The element 55 includes a rear member 57 and a pair of spaced lateral members 59 and 61. The member 57 is secured to the front end of the slideable member 63 mounted in the slide bearing 65. The element 55 is reciprocated by the lever 67 pivotally mounted at 68 on the platform 66, said lever being connected by the adjustable link 73 to the lever 75. Lever 75 is pivoted at 77 and is urged forward to follow the cam 71 by the spring 79. The spring 79 forms part of the safety mechanism since if a container is improperly positioned, it will be acted upon only by a resilient pressure insufficient to damage it. When held stationary by the finger 150 and the element 55, the conveyor belt 56 slides along thereunder. The cams 163 and 71 are driven in synchronism with the other mechanisms of the machine 30 by being mounted on the shaft 54.

The hopper means 36 includes a stationary partial cone 117, a stationary rim 118, and a rotatable disc 120. The disc is concentrically mounted on a short shaft 122 which is journaled in a bracket 124 extending rearwardly and up from the rim 118. The disc is rotated in a clockwise direction (Fig. 4) by a pulley 126, and a belt 128, the latter being driven by a motor (not shown). The disc 120 has a plurality of pins 130 which are axially reciprocated by cams (not shown) so that the pins 130 project into the cone 117 and enter the hollow depression 201 (Fig. 2A) of a cap generally indicated by reference character 203. When the pins 130 overlie the trough 132, they become retracted so that the caps 200 drop down into the trough 132, the caps resting on edge in a position substantially parallel to the plate 120.

The trough 132 includes an inner wall 134, an outer wall 136 and a bottom wall 138, and it is supported on the rim 118. The forward end of the trough 132 leads into the upper end of the cap transfer means, which includes the cap inversion mechanism 144 and the chute 140. The trough 132 inclines downwardly in a forward direction so the caps roll into the mechanism 140 by gravity. As best seen in Fig. 8, the forward portion of the inner wall 134 penetrates the cover 146 and is connected to irregularly shaped lip plate 148. The outer wall 136 stops at the edge 137 to meet the rear edge of the tipping member 150. The tipping member is generally vertically reciprocable, moving longitudinally between the lateral guides 152 and 156. The reciprocation of the tipping member 150 is obtained by a pin 158 which projects from the lower portion thereof and enters a slot in the forward end of a lever 162, the latter being pivoted at 166 on the rim 118. The lever 162 has an offset member 168 carrying a roller 170 on its end, which roller acts as a follower for a lever 172. The pin 158 extends through the cover plate 174 which has an elongated slot 176. The upper end of the lever 172 has

a shoe 178 which coacts with the roller 170. The lever 172 is in two parts, an upper part 180 and a lower part 182. The upper part 180 is pivotally connected at 184 by a bracket 186 to the right edge portion of the top plate 90 (Fig. 2). The lower part 182 is pivotally connected at 188 to the lower end of the upper part 180, the lug 190 being drawn against the edge 192 by the spring 194. The spring 194 is assisted by the spring 196 which extends between the part 182 and the anchor 198 projecting upward from the base member 202 for the safety mechanism 49. The lowermost end 204 of the lower part 182 of the lever 172 terminates in a roller 206 (Fig. 9) which acts as a follower for the cam 208 (Figs. 13, 14 and 15).

The cam 208 is integral with the forward end of lever 210, the rear end of which is pivotally mounted at 212 on a rearward extension of the bottom plate 92 (Fig. 16). The lever 210 has a roller 214 which acts as a follower for the cam 216, so that when the roller 214 follows the cam 216, for every single revolution of the shaft 54, one cap 200 is fed. The lever 210 is urged to follow the cam 216 by the spring 218, the right end of which is connected to said lever, and the left end (not shown) is suitably anchored. The lever 210 may be prevented from operating by a hook 220 on the left end of a lever 222, the right end of which is pivotally mounted by the bolt 224 on the post 104. The hook 220 is adapted to engage the lug 226 on the forward end of the lever 210. The lever 222 is normally urged upward to a position of disengagement by a spring (not shown) which is connected at its lower end to said lever and at its other end is suitably anchored, while said lever is pushed down to a position of engagement by the adjustably mounted pin 228 in the extension 230 extending to the left from the forward arm 232 of the lever 234. The forward arm 232 is bifurcated, forming a pair of fingers 234 and 236 having inwardly extending rollers which ride in an annular groove 238 of the cap transfer means 40 (Fig. 2).

Turning now from the structure just described for moving a cap 200 from the trough 132 into the chute 140, or preventing such movement; back to Figs. 4, 5, 6 and 8, in Fig. 4 is seen the position of the parts as a cap 200 is ready to be pushed into the chute. In Fig. 5, the tipping member has been elevated so that the cap is pushed over the precipice 151. As seen in Fig. 8, the cap turns over because its center of gravity is to the right, or it is assisted in so turning over by contact with the inner surfaces of the cover 146. The slot 147 permits inspection. The cap now inverted slides down the chute 140 to the exit 141 thereof and is deposited in the cap transfer means 40. It may be noted at this point that while during normal operation, the trough is preferably kept loaded with caps, the chute 140 is kept empty, being used as a passage for each individual cap which is fed into the chute by the tipping member 150 as needed.

The cap transfer means 40 receives a cap from the chute exit 141 and drops it into the mouth 99 of a container 100 (Fig. 2A). The left open edge of the exit 141 (Fig. 9) is in juxtaposition with the right edge of the means 40 which is composed of a plurality of laminated members. The bottom member is a ring 240, while the one next above is an orificed plate 242. Above the last mentioned plate are two U-shaped plates 244 and 246 opening to the left followed by shoe 248. Above these last mentioned members is a U-shaped back stop 250 which opens toward the right (Fig. 3). The

ring 240 is attached to the plate 242 while the rest of the members are suitably integrated and mounted upon the lower ends of a pair of rods 252 and 254. The rods 252 and 254 have enlargements 256 and 258 and are slideably mounted in the sleeve 260 which is fixed to the base member 202 secured to the bottom plate 92.

Disposed above the plate 242, and at the level of the plate 244 is a gate 262 which is pivotally mounted at 264 on the plate 242 to swing in a clockwise direction from the position shown in Fig. 3. The gate 262 is articulately connected by the link 266 to the right end of a short lever 268, the latter being pivoted at 270 on plate 242. The gate 262 is urged to the closed position thereof in which position it vertically supports a cap from underneath, by the contractile spring 272, the rear end of said spring being anchored on the link 266 and the forward end of said spring being anchored on a pin 274 projecting from the plate 242. The gate 262 is opened by the follower 276 which is driven by the roller 278 carried by the pusher 280. The pusher 280 is adjustably secured to the extension 282 on the plunger 284 which is slideably mounted in the sleeve 260. Plunger 284 has two spaced flanges at the upper end thereof between which lies the groove 238 previously referred to.

The transfer means 40 is connected by the safety mechanism 41 to the finger 234 of the bifurcated arm 232, see Fig. 10. The plate 242 is pivotally attached at 286 to a first connector element 288, said element having an indentation 290 and an elongated depression 292 on the inner edge 35 294 thereof.

The lower portion of the connecting member 288 is provided with a tab 291. A pivotal mounting 293 provides means for mounting a symmetrical connecting member 295. Like member 288, member 295 has therein an indentation 291, and an elongated depression 293. The upper portions of members 288 and 295, are resiliently connected by means of a contractile spring 302. This spring normally holds the members 288 and 295 in the position shown in Figure 10, wherein the pin 304 engages the sides of the opening formed by the indentations 291 and 293. Under excessive downward pressure of the pin 304, the connecting members 288 and 295 will be forced out 45 permitting the pin to ride in the slot formed by the depressions 292 and 293.

The cap closing means 48, as may be seen on Figures 18 to 21, is supported in the plate 90, the bracket 306, and the collars 308 and 310. The upper portion 312, of the bracket 306, is modified to engage a flat tab 314, rigidly secured to the main spline 316, by any suitable means such as the rivets 318, and serves to prevent the spline 316 from rotating. A plug 320 forms the upper terminus of the rotating sleeve 322. Threaded on the upper portion of the sleeve 322 are the lock nuts 324 and 326, and an upper race element 328. The first two serve to position the third axially 55 with respect to the sleeve, whereby the upper portion thereof may be supported by the ball bearings 330, which are held in place by the cage 332 in a well known manner. The lower raceway 334 is supported by the lower supporting member 336 of the bracket 306. The gear 338 transmits rotational motion from the gear train 114 (see Fig. 1). A key 340 slideably movable in the keyway 342 allows the gear 338 to be movable axially with respect to the sleeve. The gear 338 is maintained in a position to clear the bolts 344 by the

collar 346. The bolts 344 rigidly secure the collar 310 to the plate 90.

Below the collar 310 is the intermediate thrust element 343. It is secured to the sleeve 322, by suitable means, such as the set screw 350. Together with the upper intermediate race 352 it rides on the ball bearings 354.

The collar 308 has provided therein an annular groove 356, through which the links 358 transmit the reciprocation of the arm 360 (see Fig. 13). An intermediate bearing 362 allows relative rotating between the collar 308, and the sleeve 322.

The lower bearing assembly 364, is generally similar in construction to the other bearings herefore described, including an upper race 366, a lower race 368, a retainer 370, and balls 372.

Contacting the bearing assembly 364 is an elongated outer sleeve 374, the upper portion 375 of which may be knurled to facilitate grasping by the hand of the operator. The frusto conical portion 378 has a channel 380 enclosing a coil spring 382 therein. Extending within the channel 380 and contacting the lower terminus of the spring 382 is the crimpler retaining element 394 which encloses the lower portion of the sleeve 322 and is secured to the sleeve, by any suitable means such as the setscrew 385. The lower portion 388 of element 384 is of a considerably larger diameter than the upper portion 390 and is provided with a pair of slots in which the crimpler elements 394 may be pivotally mounted by means of the pins 392.

The crimpler elements 394 include a main body portion 396, a roller 398, and a crimping member 402. The roller 398 normally rests on the circular surface 404 of the outer sleeve 374.

The lower terminus of the spline 316, is secured by means of a pin 406 to a coupling 408. A shorter spline 410 is similarly secured to the coupling 408 by the pin 412. The coupling is provided to facilitate rapid and easy changing of crimping elements when so desired.

The element 384 is provided with a threaded orifice 414 in which a spacing element 416 is engaged. A ball bearing assembly 418 allows relative rotation between the spacing element 416 and the stationary cap engaging head 420.

The head 420 is secured to the spline in any suitable manner as for example by means of a bolt (not shown).

Although the operation of the cap closing means 48 will be more fully described in another portion of this disclosure, it might be noted that the splines 316 and 416 when the machine is in operation, are stationary, power from the gear 338 being transmitted through the sleeve 322. A downward force transmitted through the links 358, results in the entire mechanism below the collar 310 moving downwardly, until the head 420 engages the cap 200 of the container 100. Continued downward force, causes the outer sleeve 374 to move relative to the sleeve 322, whereby the frusto conical portion 378 contacts the rollers 398 of the crimpler element 394, thereby engaging the edges 402 with the rim of the cap.

As may be seen on Figure 9 the safety device 49 cooperates with the cap closing means 48, and comprises generally an upper portion 422, and a lower container spacing member 424. The upper portion 422 comprises generally a support link 426, part of which is secured to one of the links 358, and which provides a base for the mounting of the main body element 428. The two are maintained together by any suitable

75

means such as screws 430. An outer casing element 432 contacts small coil springs 434 at their outer terminals, the other terminals maintaining resilient pressure against two ball detents 436. A finger element 438, is slideably disposed in a channel 440 and is held in a lowered position by the engagement of the ball detents 436 in an annular groove 442. Excessive pressure on the bottom of the finger 438 will unseat the ball detents 436. The finger may be returned to its operative position manually by pressing downwardly upon the surface 444.

The lower portion 424 of the device 49 includes generally a main body element 446, a shaft 448, a coil spring 450, a retaining member 452, and a finger member 454. An upper contact member 456 is engageable with the finger member 438. The spring 450 normally urges the shaft in an upward direction, so that the retaining member 452 contacts the lower surface of the plate 92. Downward movement of the links 358 is transmitted through the upper portion 422, element 438 engaging the top member 456. The finger 454 is displaced downwardly, whereby the wedge shaped portion 458 enters the space between the two successive containers 100. If the containers should happen to be slightly displaced from their proper position the wedging action of the finger 454 tends to correct this displacement. If the displacement of the containers is so great that the finger 454 strikes the top portion of one of the containers, the finger transmits the pressure through the shaft 448 to the upper portion 442, which action dislodges the ball detents to allow the element 438 to displace upwardly.

Referring now to Figure 13, the shaft 54 in addition to driving the cams 71 and 163, drives the wheel 460. The upper surface of the wheel is modified to form the cam 462 which through cam follower 464 drives the arm 360. The arm is urged to follow the profile of the cam 462 by a coil spring 466 (Fig. 16), one terminus of which is secured to the arm, the other of which is suitably fixed to a stationary member of the frame (not shown). The arm 232 is driven in a similar manner from the cam 468 formed by the lower surface of the wheel 460, the cam follower 470 being urged to follow the cam surface by the spring 472. The arms 360 and 232 are suitably mounted for pivotal movement at 474 and 476 respectively.

Turning now to the second embodiment, to avoid needless repetition certain of the parts corresponding to those in the first embodiment have been designated by similar reference characters with the addition of the suffix *a*.

As may be seen on Figures 22 through 27, the second embodiment differs from the first embodiment principally in the means whereby a cap 200 is positioned upon a container 100. This embodiment features a magnetic cap chuck, and a somewhat modified gate opening mechanism, best seen on Figure 22.

The cam 216*a*, rotatably driven by the shaft 54*a* contacts the cam follower 478*a*, mounted on lever 480*a* rotates about the pivotal mounting 482*a*, and is urged to follow the cam by the spring 484*a*. The gate 262*a* is an elongated member a portion of which is rotatably fixed to the lever 480*a* at 482*a*.

As may be seen on Figure 27 the cam 468*a* is somewhat altered from that of the first embodiment, having an additional small depression 488*a* therein. The purpose of the depression is to enable the magnetic cap chuck to be lowered

slightly whereby it may engage a cap 200a after the time of delivery from the hopper mechanism (Fig. 26). When the gate is opened, the arm 232a drives the chuck downwardly, thereby engaging the cap firmly in the orifice in the container 100 (Fig. 27). The static friction caused by this engagement, allows the chuck to be withdrawn by the arm 232a without disturbing the position of the cap.

It may thus be seen that I have invented a novel automatic capping machine, in which the caps employed may be crimped over the openings of the containers to produce an efficient seal, which acts upon the containers at a rapid rate, and which stops the capping operations when the containers are improperly positioned so as to prevent damage to the machine, the containers or the caps.

I wish it to be understood that I do not desire to be limited to the exact details of structures as set forth in this specification, as obvious modifications will occur to those skilled in the art, without departing from the spirit of the invention.

I claim:

1. In a capping machine for use with containers and caps therefor, said machine having a relatively fixed frame, a container conveyor means, a reciprocating cap closing means supported upon a reciprocating arm operated by a cam engageable with said arm; the improvement comprising means to align successive containers beneath said cap closing means as said cap closing means is lowered to a cap closing position; said means including a reciprocating shaft having a wedge-shaped container engagement portion slidably and resiliently mounted for vertical movement upon said frame; means upon said arm adjacent

and movable with said cap closing means engageable with said shaft to move the same downwardly upon the lowering of said arm to align successive containers moving upon said conveyor means directly beneath said cap closing means.

2. A device as claimed in claim 1 in which said last mentioned means includes a finger slidably mounted for vertical movement with respect to said arm and engageable with said shaft; and resilient detent means maintaining said finger in normal operating position; whereby upon the lowering of said arm and shaft the direct contact of said wedge-shaped engagement portion with a horizontally disposed surface of a container occurs, said finger is moved upwardly from normal operating position to prevent damage to said finger and shaft.

MANUEL S. RESINA.
